UNITED STATES PATENT OFFICE.

JOHN L. SEBASTIAN, OF SALT LAKE CITY, UTAH.

DEEP-WELL PUMP.

1,106,850.

Specification of Letters Patent. Patented Aug. 11, 1914.

Application filed December 7, 1911, Serial No. 664,830. Renewed January 14, 1914. Serial No. 812,157.

To all whom it may concern:

Be it known that I, JOHN L. SEBASTIAN, a citizen of the United States, residing at Salt Lake City, in the county of Salt Lake 5 and State of Utah, have invented new and useful Improvements in Deep-Well Pumps, of which the following is a specification.

The present invention relates to improvements in deep well pumps, the object of the 10 invention being to provide a pump for use pressed air under what is known as the Starrett method of pumping, as disclosed in U. S. Letters Patent to D. W. Starrett, dated May 29th, 1906, No. 821,677, and in which, in addition to a main stream of compressed air forcing the water or other liquid out of a chamber and upwardly in a discharge pipe, there is also employed an auxiliary stream, or "jet", entering the stream of upwardly 15 flowing liquid immediately above said chamber, so that the column ascending in said discharge pipe, instead of consisting wholly of liquid, consists of liquid and air. To apply this method practically it is necessary 20 to employ a shifter to alternately direct the compressed air into one of two chambers, to expel the water or other liquid therefrom into the discharge chamber, while the other chamber is being filled with water or 25 other liquid from the well or other body of water which is being pumped. Heretofore it has not been found practicable to employ this method for pumping from deep wells owing to the difficulty of arranging the 30 different chambers within the narrow space permitted in such wells. My invention has for its object to overcome this difficulty.

In the accompanying drawing, Figure 1 is 35 a broken vertical section, certain parts being shown in side elevation, of a pump constructed in accordance with my invention; Fig. 2 is a similar section of the upper portion of the pump taken at right angles to the section shown in Fig. 1; Figs. 3, 4, 5, 6, 40 and 7, are horizontal sections on the lines 3-3, 4-4, 5-5, 6-6, and 7-7, looking in the directions of the respective arrows.

Referring to the drawing, 1 indicates the exterior cylinder of my improved pump, 45 and 2 indicates an interior cylinder, forming the wall of a discharge chamber 3, and connected to the exterior cylinder by opposite and diametrically extending webs 4, all of the above parts being formed integral 50 with each other. The interior cylinder and

the webs do not extend so far at their upper and lower terminal portions as the exterior cylinder. In the upper end of said exterior cylinder is inserted, with a tight fit, a cylindrical flange 5 of an upper head 6, comprising upper and lower transverse parallel webs 7, 8. These webs form with the flange 5 a chamber 9 which, for a reason which will hereinafter appear, I term a jet chamber. The form of this chamber is best 60 shown in Fig. 5, and it will be seen that the chamber is not co-extensive laterally with the head, but is diminished in extent by two projections 10 from the flange 5, extending between the planes of the webs. The upper 65 web 7 is formed with a large screw-threaded aperture 11, slightly eccentric to said head, and into which is screwed the lower end of the discharge pipe 12, through which the water or other liquid is expelled 70 from the chamber 9, and with a screw-threaded aperture 13, into which is screwed a small compressed air pipe 14, provided with a non-return valve, indicated at 15, and discharging a jet of compressed air into 75 the chamber 9, which I therefore term the jet chamber. Into threaded apertures 16 through said projections 10 are screwed the lower ends of pipes 17, which are used alternately as compressed air and exhaust 80 pipes, said pipes thus communicating 85 respectively with chambers 18 on opposite sides of the webs 4.

The lower diaphragm is formed with a central aperture 19 and depending flanges 20, 90 each of which, as shown in Fig. 6, extends snugly around one-half of the upper edge of the interior cylinder 2, then in close proximity to the upper edges of the webs 4, as shown at 21, and is then integrally 95 connected to the lower portion of the cylindrical flange of the head 6, fitting snugly, as shown at 22, against the interior surface of the exterior cylinder. Said portions 21 of said flanges thus form grooves, the upper 100 edges of the webs 4 forming tongues, which fit snugly in said grooves and prevent the passage of compressed air from one to the other of the semi-annular chambers 18 which are formed between the interior and exterior cylinders.

The lower terminal portion of the exterior cylinder 1 is formed with an annular recess 24, terminating in an outwardly extending flange 25, to which is attached, by 110

screws 26, an inlet valve casing 27 having a central partition 28 dividing it into two chambers 23, in each of which can operate a flap valve 29, closing an inlet opening 30 into said chamber 23. On a packing strip 31 resting upon the upper edge of the partition 28 is supported a valve casing 32, best shown in Figs. 1 and 7, having oppositely and diametrically extending vertical webs 33, the outer edges of which extend into contact with the internal surface of the exterior cylinder 1 and are there formed with flanges 34. The upper portion of the valve casing 32 is formed with flanges 35, which fit snugly around the lower edge of the interior cylinder 2. The upper edges of the webs 33 are forked or grooved, as shown at 36, to receive the lower edges of the webs 4. Below said flanges the valve 20 casing 32 is of a form substantially square in horizontal section, and the portions of the valve casing which lie on opposite sides of the central plane through said webs taper inwardly downward, as shown in Fig. 1. 25 The lower portion of said valve casing, resting upon the packing strip 31, is formed with a diametral socket or bearing 37 to receive the knuckle 38 of a valve 39 vibratable upon a pivot pin 40, said valve being 30 adapted to alternately close ports 41 in said tapering portions of the valve casing.

The flap valves 29 on the side adjacent the inlet openings and the valve 39 on each side thereof are provided with leather facings 42 held on said valve by plates 43 screwed to the valves.

The following is the mode of operation of my improved pump. By means of a shifter, the construction of which forms no part of the present invention, compressed air is admitted by one of the pipes 17, say that on the left in Fig. 1, while the other pipe 17 is open to exhaust. The compressed air thus admitted expels the water or other liquid from the chamber 18 on the left through the port 41 on the left into the chamber 3 and thence into the jet chamber 9 and discharge pipe 12, compressed air being also admitted by the jet pipe 14 into the jet chamber 9 and passing up with the water or other liquid into the discharge pipe, in the manner explained in said patent to Starrett. The inlet opening 30 on the left is closed by the pressure of the compressed air in the chamber 18 on the left, but the inlet opening 30 on the right is opened by the upward pressure of the water or liquid in the well or other body of water being pumped, which liquid flows upwardly into the chamber 18 on the right at a rate determined by the degree of submergence of the pump. Before so much of the water or other liquid in the chamber 23 on the left 60 has been expelled therefrom that its level

is below the level of the port 41, the before-mentioned shifter is operated, so that the compressed air flows by the pipe 17 on the right, while the pipe 17 on the left is open to exhaust. The valve 29 on the left immediately opens, while the valve 29 on the right closes, the valve 39 swings to its position on the left, and the water or other liquid is expelled from the chamber on the right, as already explained. 75

I claim:

1. In a deep well pump, the combination of exterior and interior cylinders, webs connecting said cylinders and dividing the space between them into chambers, a head fitting 80 snugly within the exterior cylinder and connected to the upper end of said interior cylinder, and having apertures registering respectively with the interior cylinder and the chambers, a discharge pipe connected with 85 the interior cylinder, a jet pipe communicating with the discharge pipe above said interior cylinder, pipes connected with said chambers for supplying compressed air thereto and exhausting therefrom, a valve 90 casing connected to the lower end of the interior cylinder and having openings communicating with said chambers, a valve adapted to alternately close said openings, an inlet casing connected to the lower end of 95 the exterior cylinder having a partition forming with said casing compartments respectively communicating with said chambers, said compartments having inlet openings, and non-return valves closing said 100 openings.

2. In a deep well pump, the combination of exterior and interior cylinders, webs connecting said cylinders and dividing the space between them into chambers, a head fitting 105 snugly within the exterior cylinder and connected to the upper end of said interior cylinder, said head being provided with upper and lower transverse webs spaced from each other to form a jet chamber, said webs having apertures, the upper end of the interior cylinder being secured in the aperture in the lower web, a discharge pipe connected to 110 said upper web through an aperture therein, a jet pipe connected with said jet chamber through an aperture in the upper web, pipes connected with said chambers for supplying compressed air thereto and exhausting therefrom, a valve casing connected to the lower end of the interior cylinder and 115 having openings communicating with said chambers, a valve adapted to alternately close said openings, an inlet casing connected to the lower end of the exterior cylinder having a partition forming with said inlet 120 casing compartments respectively communicating with said chambers, said compartments having inlet openings, and non-return valves closing said 125 openings.

3. In a deep well pump, the combination 130

of exterior and interior cylinders, webs connecting said cylinders and dividing the space between them into chambers, a head fitting snugly within the exterior cylinder and connected to the upper end of said interior cylinder, said head being provided with upper and lower transverse webs spaced from each other to form a jet chamber, and with parts forming tongue-and-groove joints with the webs, said webs having apertures, the upper end of the interior cylinder being secured in the aperture in the lower web, a discharge pipe connected to said upper web through an aperture therein, a jet pipe connected with said jet chamber through an aperture in the upper web, pipes connected with said chambers for supplying compressed air thereto and exhausting therefrom, a valve casing connected to the lower end of the interior cylinder and having openings communicating with said chambers, means for alternately closing said openings, an inlet casing rigid with the lower end of the exterior cylinder and having a partition forming with said casing compartments respectively communicating with said chambers, said compartments having inlet openings, and non-return valves closing said openings.

5. In a deep well pump, the combination of exterior and interior cylinders, webs connecting said cylinders and dividing the space between them into chambers, a head fitting snugly within the exterior cylinder and connected to the upper end of said interior cylinder, said head being provided with upper and lower transverse webs spaced from each other to form a jet chamber, said webs having apertures, the upper end of the interior cylinder being secured in the aperture in the lower web, a discharge pipe connected to said upper web through an aperture therein, a jet pipe connected with said jet chamber through an aperture in the upper web, pipes connected with said chambers for supplying compressed air thereto and exhausting therefrom, a valve casing connected to the lower end of the interior cylinder and having openings communicating with said chambers, means alternately closing said openings, an inlet casing rigid with the lower end of the exterior cylinder having a partition forming with said inlet casing compartments respectively communicating with said chambers, said compartments having inlet openings, and non-return valves closing said openings.

6. In a deep well pump, the combination of exterior and interior cylinders, webs connecting said cylinders and dividing the space between them into chambers, a head fitting the exterior cylinder and connected to the upper end of said interior cylinder, said head being provided with upper and lower transverse webs spaced from each other to form a jet chamber, said webs having apertures, the upper end of the interior cylinder registering with the aperture in the lower web, a discharge pipe registering with an aperture in the upper web, a jet pipe connected with said jet chamber through an aperture in the upper web, pipes connected with said chambers for supplying compressed air thereto and exhausting therefrom, a valve casing connected to the lower end of the interior cylinder and having openings communicating with said chambers, means alternately closing said openings, an inlet casing rigid with the lower end of the exterior cylinder having a partition forming with said inlet casing compartments respectively communicating with said chambers, said compartments having inlet openings, and non-return valves closing said openings.

7. In a deep well pump, the combination of exterior and interior cylinders, webs connecting said cylinders and dividing the space between them into chambers, a head fitting the exterior cylinder and connected to the upper end of said interior cylinder, said head being provided with upper and lower transverse webs spaced from each other to form a jet chamber, and with parts forming tongue-and-grooved joints with the webs, said webs having apertures, the upper end of the interior cylinder being connected with the aperture in the lower web, a discharge pipe connected to said upper web through an aperture therein, a jet pipe connected with said jet chamber through an aperture in the upper web, pipes connected with said chambers for supplying compressed air thereto and exhausting therefrom, a valve

- casing rigid with the lower end of the interior cylinder and having openings communicating with said chambers, means for alternately closing said openings, an inlet 5 casing connected to the lower end of the exterior cylinder having a partition forming, with said inlet casing, compartments respectively communicating with said chambers, said compartments having inlet openings, and non-return valves closing said 10 openings.
8. In a deep well pump, the combination of exterior and interior cylinders, webs connecting said cylinders and dividing the space 15 between them into chambers, a head fitting snugly within the exterior cylinder and connected to the upper end of said interior cylinder, said head being provided with upper and lower transverse webs spaced from each 20 other to form a jet chamber, said webs having apertures, the upper end of the interior cylinder being connected with the aperture in the lower web, a discharge pipe connected to said upper web through an aperture 25 therein, a jet pipe connected with said jet
- chamber through an aperture in the upper web, pipes connected with said chambers for supplying compressed air thereto and exhausting therefrom, a valve casing rigid with the lower end of the interior cylinder 30 and having openings communicating with said chambers, means for alternately closing said openings, said head making air tight joints with said webs, an inlet casing rigid with the lower end of the exterior cylinder, 35 having a partition forming with said inlet casing compartments respectively communicating with said chambers, said partition making an air tight joint with said valve casing, said compartments having inlet 40 openings, and non-return valves closing said openings.

In testimony whereof I have hereunto set my hand in the presence of two subscribing witnesses:

JOHN L. SEBASTIAN.
